US0D1018357S

(12) **United States Design Patent** (10) **Patent No.:** **US D1,018,357 S**
(45) **Date of Patent:** **** Mar. 19, 2024**

(54) **NECKLACE**

(71) Applicant: **Jianhua Wang**, Guangzhou (CN)

(72) Inventor: **Jianhua Wang**, Guangzhou (CN)

(73) Assignee: **Jianhua Wang**, Guangzhou (CN)

(**) Term: **15 Years**

(21) Appl. No.: **29/817,723**

(22) Filed: **Dec. 3, 2021**

(51) **LOC (14) Cl.** **11-01**

(52) **U.S. Cl.**

USPC **D11/16**

(58) **Field of Classification Search**

USPC D11/1-5, 12-16; D30/152

CPC A44C 11/00

(57) **CLAIM**

The ornamental design for a necklace, as shown and described.

DESCRIPTION

FIG. 1 is a perspective view of a necklace showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is an enlarged view of portion 10 shown in FIG. 2. The dot-dash broken lines represent boundaries of the enlarged portions and form no part of the claimed design.

1 Claim, 10 Drawing Sheets
